U.S. Appl. No. 10/919,494, filed Aug. 7, 2004, Stein.

Primary Examiner—Holly H. Baynham

(74) Attorney, Agent, or Firm—Jones Day; Brett Lovejoy

(57) **CLAIM**

The ornamental design for a hanging clip, as shown and described.

DESCRIPTION

FIG. 1 is a front right perspective view of an ornamental design for a hanging clip according to the present invention;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a front right perspective view in an exemplary use position.

All portions shown in broken lines are environmental and illustrative only, and form no part of the claimed design.
